UNITED STATES PATENT OFFICE

105,781

DESIGN FOR A FUR COAT OR SIMILAR ARTICLE

Murray Schotland, Cedarhurst, N. Y.

Application July 7, 1937, Serial No. 70,293

Term of patent 3½ years

To all whom it may concern:

Be it known that I, Murray Schotland, a citizen of the United States, residing at Cedarhurst, county of Nassau, and State of New York, have invented a new, original, and ornamental Design for a Fur Coat or Similar Article, of which the following is a specification, reference being had to the accompanying drawing, forming a part thereof.

The design is characterized by a generally straight swagger body of leopard cat fur in contrast with square raglan sleeves and collar of lustrous sheared beaver.

I claim:

The ornamental design for a fur coat or similar article, as shown and described.

MURRAY SCHOTLAND.
